UNITED STATES PATENT OFFICE.

ARTHUR CARSON, OF MELBOURNE, VICTORIA, AUSTRALIA, ASSIGNOR
OF ONE-HALF TO JOHN SHAW GREER, OF MELBOURNE, VICTORIA,
AUSTRALIA.

SAFETY HOUSEHOLD-LAMP.

SPECIFICATION forming part of Letters Patent No. 729,542, dated June 2, 1903.

Application filed June 12, 1902. Serial No. 111,382. (No model.)

To all whom it may concern:

Be it known that I, ARTHUR CARSON, a subject of the King of Great Britain, residing at No. 454 Collins street, Melbourne, in the State of Victoria, Australia, have invented new and useful Improvements in Safety Household-Lamps, of which the following is a specification.

The object of this invention is to provide a lamp for household use in which the light will be extinguished on the lamp being overturned, so obviating the present danger in the use of kerosene-lamps. The invention also provides a simple means for extinguishing the light at any time desired. Further, the lamp is constructed so that the light will be extinguished if dropped by a person carrying the lamp.

In order that the invention may be clear, I will now describe same with reference to the accompanying sheet of drawings, in which—

Figure 1 represents a vertical section taken through a lamp provided with the improvements. Fig. 2 shows an outside view of movable sleeve and its connections. Fig. 3 shows the movable parts in their altered position in relation to the fixed parts.

The invention is illustrated as applied to one form of lamp having a circular wick; but it will be understood that the lamp might be made of various designs with straight wick, single or double.

1 represents the lamp-reservoir, on which is mounted the wick-carrier or burner 2, that has the channel 3 for the passage of the wick and the opening 4 for the air-inlet. Within the burner is set a cylinder 5, that is mounted on a rod 6. The cylinder 5 is perforated with holes for the admission of air. A conical sleeve 7 encircles the burner 2, and this is connected to the cylinder 5 by means of a screw 8, which passes through plate 9, attached to the said sleeve. The rod 6 proceeds through a tube 10, that is passed through the reservoir of the lamp and which screws at its base into the frame 11 of the lamp at the base of the reservoir. The frame 11 is mounted on tube 12, that is supported by base 13 of the lamp. In the drawings the tube is illustrated as being held in position by a nut 14. The rod 6 rests upon a disk or guide 15, and this disk or guide is connected

by a link 16 to one arm of a lever 17 and is centered on pivot-bearing in the tube 12. The other arm of the lever 17 is connected by a link 19 with a weight 20, which normally rests upon the table supporting the lamp. 55

Means are provided for holding the rod 6 when the lamp is to be lifted and the light kept burning and which consists of an arm or lever 21, articulated to the frame 11 and arranged to bear upon a pin 22, that passes through the frame 11 and tube 10 and butts against the rod 6.

23 represents the lamp-wick, that is moved in the ordinary way. 65

25 represents the ordinary support for the lamp-chimney, and 26 an outer casing supported on the base and which serves a purpose in the particular design of lamp here shown. 70

When the invention is applied to a lamp with a flat wick or wicks, the cylinder 5 will be dispensed with and the sleeve 7 will be of a shape to correspond with and fit upon the burner, and said burner will be secured directly to the rod 6. 75

The *modus operandi* of the invention is as follows: When in ordinary use with the light burning, the parts will be in the relative positions shown in Fig. 1, with the weight 20 resting on the table, and the rod 6, with the cylinder 5 and sleeve 7, in the "down" position. Should the lamp be overturned, the weight 20 will fall and operate the lever 17 to raise the disk 15, and so force up the rod 6 and with it the cylinder 5 and connected sleeve 7, so causing the instant extinction of the light, the parts being now in the relative position shown, Fig. 3. By lifting the lamp from the table the same effect will be obtained and the light extinguished, if so desired; but if it is desired to move the lamp without extinguishing the light the lever 21 may be pressed with the thumb in the act of lifting the lamp, which will cause the pin 21 to act on the rod 6 to hold the parts in the positions shown on Fig. 1. Should the lamp be dropped accidentally, the pressure being released from the lever 21 the parts will immediately act to extinguish the light. 95

Having now particularly described and ascertained the nature of my said invention and

in what manner the same is to be performed, I declare that what I claim is—

1. In a household-lamp, in combination a central tube 6 passing through lamp-reservoir 5 and an enlarged tube 12 at the base of same, a rod 6 passing through the tube 10 and carrying a cylinder 5 within the burner and a sleeve 7 connected therewith outside the burner, a disk 15 within the tube 12 supporting the rod 6, a lever 17 on pivot within the tube and connected on the one side to the disk 15 and the other side to weight 20 and means for holding the rod 6 substantially as and for the purposes described.
2. In a household-lamp, in combination a central tube 6 passing through lamp-reservoir and entering frame 11, an enlarged tube 12, supporting frame 11 a rod 6 passing through

the tube 10 and carrying a cylinder 5 within the burner and a sleeve 7 having opening 4 20 and connected with cylinder 5 by cross-bar 9 and pin 8, a disk 15 within the tube 12 supporting the rod 6, a lever 17 on pivot within the tube and connected on the one side to the disk 15 and the other side to weight 20, a 25 pin 22 passing through frame 11 and tube 10 and a pivoted lever bearing upon said pin substantially as and for the purposes described.

In testimony whereof I have signed my 30 name to this specification in the presence of two subscribing witnesses.

ARTHUR CARSON.
